COKING RETORT OVEN

Joseph Becker, Pittsburgh, Pa., assignor to The
Koppers Company of Delaware, Pittsburgh, Pa.,
a corporation of Delaware

Application October 25, 1932, Serial No. 639,448

22 Claims. (Cl. 202—142)

This invention relates to improvements in coking retort ovens. It has general applicability and utility in various horizontal coke ovens, and more particularly in ovens of the type, among others, of the well-known cross-over ovens exemplified in the Joseph Becker Patent No. 1,374,546 granted to The Koppers Company under date of April 12, 1921, and in other patents relating thereto. The invention has for an object the provision of improved uniformity and regulation of heat distribution and improved fuel-economy in such ovens; and has for further objects such other operative or structural advantages or results as may be found to obtain in the structures and operation hereinafter described or claimed.

Among other considerations, it is of consequence in such ovens that the heating effected by the burning of combustion media in the heating-flues shall be distributed with great uniformity over the extended heating-wall faces contiguous to the coal charges in the coking-chambers between such heating-walls, and that regulation of such heating shall be facilitated by a method of distribution of the heating media that tends automatically to correct and to compensate irregularities due to localized over-heated or under-heated regions in the heating-walls, and also that fuel-economy may be promoted by remedying the over-consumption of fuel-gas that may result from localizing of flame in too great intensity in portions of the heating-flues without sufficiently extending and distributing through such flues the flame of the burning fuel-gas, especially in view of the fact that the coking of the coal charge is mainly effected by the direct radiant flame-heat rather than by the limited further heat derived from the hot combustion-products that flow off from the burning flame-flues. A certain minimum of fuel-gas must be burned to furnish the heat requirement for the coking of a given coal charge, and a certain minimum of air for combustion must be supplied to such fuel-gas, and the flame-heat is made more effective by an extended and uniform distribution of the flame in the flame-flues and at the same time completeness of combustion of the fuel-gas with its minimum air requirement is promoted by increased and more uniform distribution of the mixture of fuel gas and air flowing through and burning in the flame-flues. Other considerations will be apparent from the description and claims hereinafter setting forth the invention.

In the accompanying drawings, forming a part of this specification and showing for purposes of exemplification certain preferred forms and man-

ner in which the invention may be embodied and practiced, but without limiting the claimed invention specifically to such illustrative instance or instances:

Fig. 1 is a vertical sectional view of a coking retort oven or oven-battery of the before-mentioned Becker type of cross-over ovens, the sections being taken crosswise of the battery on the lines D—D and E—E of Fig. 2;

Fig. 2 is a composite vertical sectional view, lengthwise of the coking retort oven or oven-battery, taken on lines A—A and B—B of Fig. 1;

Fig. 3 is a fragmentary horizontal section taken on lines III—III of Fig. 2, and showing particularly the gas and air and waste gas ports in the bases of the heating-flues, and the communications leading to such ports, in their relation to the heating-walls and intervening coking-chambers;

Fig. 4 is a composite vertical sectional view, crosswise of the oven-battery, taken on lines D—D and M—M of Fig. 2;

Fig. 5 is a merely conventional flow diagram to indicate the general course of the flow of gas and air and waste gas in and through the regenerators and heating-flues and their communications in the oven-battery illustrated in the above Figs. 1, 2, 3 and 4;

Fig. 6 is a composite vertical sectional view of a coking retort oven or oven-battery of a known type other than the cross-over type and having each heating-wall constituted of inverted U-shaped or hairpin-flues, the sections being taken crosswise of the battery on the lines F—F and G—G of Fig. 7;

Fig. 7 is a composite vertical sectional view, lengthwise of the battery of Fig. 6, and taken on the lines H—H of Fig. 6 and S—S of Fig. 8;

Fig. 8 is a fragmentary horizontal sectional view taken on lines VIII—VIII of Fig. 7 and showing particularly the gas and air and waste gas ports in the bases of the heating flues, and the communications leading to such ports, in their relation to heating-walls and intervening coking-chambers; and

Fig. 9 is a merely conventional flow diagram to indicate the general course of the flow of gas and air and waste gas in and through the regenerators and heating-flues and their communications in the oven-battery illustrated in the above Figs. 6, 7 and 8.

Like reference numerals indicate like parts in the several views of the drawings.

In the embodiment illustrated in Figs. 1, 2, 3, 55

4 and 5, the more pertinent features are as follows:

The coking retort oven or oven-battery comprises a series of horizontal coking-chambers 10 and intermediate heating-walls 12 therefor and side-by-side therewith, and series of side-by-side cross-regenerators 13, 14 below and paralleling the series of coking-chambers and heating-walls, together with the communications between said 10 heating-walls and regenerators and the further gas conduits and supporting walls and other structures shown. The heating-walls comprise vertical heating-flues 15 disposed in sets, one set in each heating-wall, the sets in pairs of mutually 15 adjacent heating-walls being mutually connected by cross-over conduits 16 through which the hot combustion-products or waste-heat gases from the up-flow or burning set of heating-flues in one heating-wall flow over to the down-flow set 20 of heating-flues in the other heating-wall of the pair, the flow being reversed and the up-flow set becoming the down-flow set and vice versa upon the reversal of the regenerative system. The lower ends of the cross-over conduits 16 port into 25 horizontal passages 17 that communicably join the top ports 18 of the heating-flues in the heating-walls. The set of heating-flues in each heating-wall, all of which flow in one direction, either upward or downward, at any one time, are disposed 30 in groups of three or four heating-flues each, the several heating-flues in each group being separated from each other by vertical partitions 19 transverse of the heating-wall, the partitions within each group stopping somewhat 35 short of the top of the heating-wall to provide the above-mentioned communicating passages 17 while the like transverse partitions 20 are partially extended all the way up to the top of the heating-wall but provided with ports 21 that communicably 40 connect the horizontal space above the heating-flues of adjacent groups and render the horizontal passages 17 substantially continuous throughout the length of the top portion of the heating-wall. The flow from or to the heating-flues in each group traverses mainly the cross-over conduit 16 that is above the middle partition 19 in such group, and the top of said middle partition is flared, at 22, beneath the adjacent port of the cross-over conduit, to promote equality 45 of flow to or from the middle heating-flues of the group and to or from those heating-flues of the same group that are farther from said cross-over conduit; and the above-mentioned ports 21 in the transverse partitions that are between the 50 groups, serve to equalize any inequalities of flow or pressure that may occur as between the tops of adjacent groups in the set of heating-flues that is comprised in the entire heating-wall. In the said set of heating-flues, comprised in the 55 heating-wall, there are about seven of the adjacent groups and a corresponding number of cross-over conduits 16 respectively serving said groups and the corresponding groups in the set of heating-flues comprised in the adjacent heating-wall of the pair. The tops of the heating-flues of each heating-wall are accessible through the usual inspection holes 23 extending to the top of the oven or battery.

The horizontal coking-chambers 10, intermediate the heating-walls, are of greater height than the heating-walls and have their opposite ends closed as usually by removable doors 24, the door on the pusher-side end of the chamber being as usually constructed with an opening 25 through 75 which the leveler bar of the pusher machine may

be entered to level off and determine the height of the top of the coal charge 26, which is commonly somewhat higher than the tops of the aforesaid heating-flues, so that, upon shrinkage of the coal in coking, the top of the coked charge 5 will still be a little above the tops of the heating-flues and thereby insure a relatively cool coke-charge top immediately below the gas-collecting crown space 27 of the coking-chamber, thereby protecting from decomposition the distillation 10 gases that collect in such crown space and flow off from the coking-chamber through the ascension pipes 28 that communicably connect the ends of the coking-chamber with the gas-collecting mains 11 mounted along the pusher-side and 15 coke-side respectively of the battery.

The aforesaid cross-regenerators, below and paralleling the series of coking-chambers and heating-walls, are disposed in groups of three, each group having a large middle gas-regenerator 20 13 flanked by two smaller air-regenerators 14, 14. The gas-regenerators 13 are adapted for pre-heating poor or weak gas, such as producer gas or blast furnace gas, but are also adapted for preheating air when the ovens are being fired 25 with strong gas, such as their own distillation gases which do not require regenerative pre-heating. The air-regenerators 14 are adapted for preheating air and in each group they flank the middle gas-regenerator 13 which is thereby 30 isolated from the regenerators of adjacent groups that are simultaneously operating for downflow or outflow of waste gases, such isolating of the gas-regenerators serving to eliminate possibilities of leakage of gas into the countercurrent flow 35 of waste gases under lower pressure in said adjacent regenerator groups. At any given time, alternate groups of regenerators operate for up-flow of gas and air and the intermediate groups for downflow of waste gases, these relations being 40 reversed at each period of reversal of the regenerative system (as set forth in, for instance, my Patent No. 1,678,802 which shows similar triple groups of regenerators). Each gas-regenerator 13 at its top communicates through two ducts 21, 45 27 with heating-flues in heating-walls that are on respectively opposite sides of the coking chamber that is directly above such gas-regenerator; and the two air-regenerators 14 that flank said gas-regenerator each communicate respectively, 50 through ducts 28, with the heating flues in one of said two heating-walls that are both in communication with said gas-regenerator. Such two heating-walls operate simultaneously in the same direction in respect of each other and respectively 55 belong to two adjacent pairs of the pairs of heating-walls that are connected by cross-over conduits 16 in the manner before described. The groups of regenerators are separated from each other by the oven supporting pillar-walls 29 that 60 are respectively located directly below those coking-chambers which are within the paired heating-walls that are connected by the cross-over conduits 16 as above mentioned. In each triple group the gas and air regenerators are separated 65 from each other by the oven supporting pillar-walls 30 that are respectively located substantially below the two heating-walls that are fed by and receive waste gas from the regenerators of said group. These pillar-walls 30 within each 70 regenerator group are of somewhat lighter structure than the pillar-walls 29 between the adjacent groups of regenerators.

The above-described regenerators are in two series lengthwise of the battery, one series for 75

the pusher-side half of the battery and the other series for the coke-side half of the battery, the cross-regenerators of the one series abutting end for end, along the lengthwise middle of the battery, with the corresponding cross-regenerators of the other series and being separated therefrom by the median longitudinal partition wall 31 that extends longitudinally along the middle of the battery transversely under the middle of the series of coking-chambers and heating-walls comprised in the superstructure above the regenerators. The gas-regenerators in the pusher-side series and coke-side series respectively are fed with gas from the gas-mains 32, 33 that extend along the pusher-side and coke-side respectively of the battery. Each gas-regenerator has two sole-channels 34, 34 extending lengthwise of the regenerator under its checkerbrick, and each air-regenerator has a sole-channel 35 extending lengthwise of it under its checkerbrick. All of the sole-channels are provided in their outer ends with air-boxes 36, all of which are provided with air inlet valves 37 and also communicate through connections 38 with the adjacent waste gas tunnel 39, one such tunnel extending along the outside of the sub-structures on either side of the battery. The air-boxes provided for the gas-regenerators are also in valved communication, through connections 40, with the respective gas-mains 32, 33, that supply gas for the gas-regenerators; and the air inlet valves for these air-boxes are at all times kept closed when the battery is being fired with gas from said gas-mains that feed the gas-regenerators. The usual reversal mechanisms are provided for operating the valves of the air and gas and waste gas connections just above mentioned, which control the inflow and outflow to and from the regenerators of the battery. When the battery is being fired with strong gas, such as its own gases of distillation, which does not require regenerative preheating but has a large air requirement, all of the connections 40 to the gas-mains 32, 33 are kept closed, and all of the air-boxes are employed for supplying air to and withdrawing waste gases from all of the regenerators of the battery, thus providing an increased supply of regeneratively preheated air by utilizing for air not only the air-regenerators 14 but also the gas-regenerators 13 that would otherwise be employed for preheating extraneously derived weak or poor gas, such as producer gas or blast furnace gas.

For alternatively firing the battery with rich gas, such as its own gases of distillation, the base of each heating-flue is provided with a gas-conduit 41 that extends directly downward to and through the foundation-mat 42 that supports the regenerators, each such conduit being provided at its lower exposed end with an individual hand-valve 43 that is accessible below the battery and by which the gas flow for the conduit may be individually regulated by the operator. Further individual pipe-connections 44 connect each conduit with a branch-header 45 that is in turn connected by a pipe 46 with a gas-main 47 that supplies gas to the battery from some reservoir-source in which the gases of distillation of the same battery, or of like batteries in the same plant, are collected and stored. There are two such gas-mains 47 extending longitudinally under the battery, one under its pusher-side half and one under its coke-side half; and there is a branch-header 45 for each such half of each heating-wall in the battery. The automatic reversing mechanism of the battery is connected

with the lever-arms 48 of the valves 49 in the pipe connection 46 between each branch-header pipe 45 and its corresponding gas-main 47. And during alternate reversal periods the supply to alternate pairs 50 of these branch headers are respectively opened and shut. The gas-conduits 41, individual to the heating-flues, are placed inside the supporting walls 30 that are within the respective regenerator groups before described, and in each instance feed gas to the same heating-walls that are fed by the same regenerator group, so that whenever gas is flowing upward through a gas-conduit 41 there is no countercurrent flow in the regenerators on either side of the wall in which that conduit is placed, but the flow through the regenerators on both sides of such wall is then in the same direction, that is, toward the heating flues, as the flow in the conduit itself, and so pressure differences are minimized on either side of such conduit and there is a corresponding minimizing of the possibility of leakage between the gas-conduit and the contiguous regenerators that are simultaneously fired with up-flowing air. When the same regenerator group is operated for waste gas outflow, the gas conduits 41 in the walls 30 within such group have already been shut off by the reversing mechanism and there is no gas flow through them that can be affected by any possibility of leakage through the walls that incase the gas conduits.

The checkerwork in the regenerators is subdivided by vertical transverse curtain-walls 52 to promote equality of distribution of flow.

Cross-under ducts 51 disposed transversely under the coking-chambers connect with each other at their lower parts the sets of heating-flues that in alternation and in mutual communication serve for up-flow and down-flow. Each such cross-under duct 51 communicably connects the base of a heating-flue in one heating-wall with the base of a corresponding heating-flue in the heating-wall on the opposite side of an intervening coking-chamber. The pair of heating-walls whose heating-flues are in this manner communicably connected by cross-under ducts 51 are in each instance a pair of heating-walls that have the before-described sets of heating-flues respectively disposed on opposite sides of the intervening coking-chamber and connected with each other by cross-over conduits 16 spanning such coking-chamber, so that the set of heating-flues in one heating-wall of the pair operates for up-flow of burning gases while the set in the opposite heating-wall operates for down-flow of the combustion-products that are led over to it by the intervening cross-over conduits 16. These down-flowing combustion products are in large part led off through the waste gas regenerators then in communication with such down-flowing set of heating-flues. But a considerable portion of the combustion products down-flowing through each such heating-flue will be both impelled and drawn through the cross-under duct 51 from the base of such heating-flue back into the corresponding up-burning heating-flue on the opposite side of the intervening coking-chamber, and there will intermix with the up-flow combustion media and the newly formed combustion products in such up-burning flue and will traverse such flue and pass on over again, through the cross-over conduits 16, into the down-flowing heating-flues, completing a cyclical recirculation through the communicably connected heating-flues on both sides of the in-

tervening coking-chamber. This latter recirculation of the hot waste gases into and through the burning heating-flues has the effect of constantly and uniformly supplying the burning flues with a neutral gaseous diluent that intermixes with the combustion media and tends to extend the flame and flame-heat uniformly throughout the height of the vertical flues that are being fired. Such heat distribution is of value and importance in any case but especially when the coking-chambers and their necessary heating-flues are of considerable height; and there is and for some time has been an increasing practice of building to much greater height than formerly the coking-chambers of horizontal coke ovens as well as of vertical coke ovens. The provision of these cross-under ducts for return recirculation of the hot waste gases accomplishes in a simple and effective manner a great uniformity of heat distribution throughout the flame-flues of greatest height that are employed in the high ovens built under modern practice.

The outflow of combustion products from the bases of down-flowing heating-flues into the corresponding outflow regenerators is regulated by the usual stack-draft regulation for the regenerators and battery; and the quantity at any time flowing out from the down-flow heating-flues into the outflow regenerators will be constantly equal to the quantity of combustion media that are being fed into the up-flow burning heating-flues communicably connected with the corresponding down-flow heating-flues. But regulation of velocities by control of stack-draft conditions, and by limitation of the apertures of the ports in the bases of the heating-flues, will control the relative amount of the considerable portion of the down-flow waste gases that are impelled and drawn out of the down-flow heating-flues into and through the cross-under ducts 51 and thence returned to the up-burning flame-flues. A certain definite proportion will constantly thus be returned, and the diluent effect in the flame-flues will be maintained as constantly uniform as are the draft regulation and fuel-gas supply of the heating-flues of the battery. There is, as it were, an automatic balance between the draft regulation and fuel-gas supply on the one hand and the waste gas return circulation on the other hand. And there is no heat loss and no irregularity of supply such as may be incident to the supplying of neutral gaseous diluent from some extraneous source. Also the flow of the return gases directly downward 55 out of the base of the down-flow heating-flue into the cross-under duct, and the discharge of such gases directly upward from the other end of said duct into the base of the corresponding up-flow heating-flue, are conditions that minimize the possibilities of developing vortices and other irregularities of flow when waste gases are returned into an up-burning flue through apertures laterally opening into it from a contiguous down-flow flue into which the up-flow flue 60 is directly discharging its combustion products.

As before said, another one of the various possible embodiments of the invention is exemplified by the form and operation of the oven illustrated in Figs. 6, 7, 8 and 9, and in the form shown in said Figs. 6, 7, 8 and 9 the main pertinent features are as follows:—

The coking retort oven or oven battery comprises a series of horizontal coking-chambers 60 and intermediate heating-walls 62 therefor and side-by-side therewith, and a series of side-by-

side cross-regenerators 63, 64 below and paralleling the series of coking-chambers and heating-walls, together with the communications between said heating-walls and regenerators and the further gas conduits and supporting walls and other structures shown. The heating walls comprise vertical heating-flues 65, 66 disposed in sets, the heating-flues 65 of one set being disposed alternately with the heating-flues 66 of the other set in each heating wall 62, and the contiguous 10 heating-flues 65, 66 being mutually connected by the passage 67 at their tops to form hairpin-flues for up-flow and down-flow of burning gases and combustion-products, the hot combustion-products or waste heat gases from each heating-flue, 15 for instance 65, in the up-flow or burning set of heating-flues flowing over into the respectively contiguous heating-flue, for instance 66, in the down-flow set of heating-flues in the same heating-wall 62, the flow being reversed and the up-flow set becoming the down-flow set and vice versa upon the reversal of the regenerative system. In adjacent heating-walls, however, on opposite sides of each coking chamber, the heating-flues, for instance 65, in one heating wall 25 that are at any time operating for up-flow are disposed opposite to the heating-flues, for instance 66, in the opposite heating-wall that are at any time operating for down-flow, so that in alternate heating-walls 62 of the battery the 30 up-flow and down-flow sets of heating-flues are reversely disposed in respect of each other. For example, in the longitudinal battery section shown in Fig. 7 and exposing four heating-walls with their three intermediate coking-chambers, 35 it will be observed that the up-flow flues in the first and third heating-walls are opposite the down-flow flues in the second and fourth heating-walls intersected by such sectional view taken transversely of the coking-chambers and 40 the heating-walls on their opposite sides; and the same relation will be apparent from the conventional flow diagram in Fig. 9. The tops of the heating-flues of each heating-wall are accessible through the usual inspection holes 73. 45

The horizontal coking-chambers 60, intermediate the heating-walls, are of greater height than the heating-walls and have their opposite ends closed as usual by removable doors 24, the door on the pusher-side end of the chamber being as usually constructed with an opening 75 through which the leveler bar of the pusher machine may be entered to level off and determine the height of the top of the coal charge 76, which is commonly somewhat higher than the tops of the aforesaid heating-flues, so that, upon shrinkage of the coal in coking, the top of the coked charge will still be a little above the top of the heating-flues and thereby insure a relatively cool coke-charge top immediately below the gas 60 collecting crown space 103 of the coking-chamber, thereby protecting from decomposition the distillation gases that collect in such crown space and flow off from the coking-chamber through the ascension pipes 104 that communicably connect the ends of the coking-chamber with the gas collecting mains mounted as commonly along the pusher-side and coke-side respectively of the battery.

The aforesaid cross-regenerators, below and 70 paralleling the series of coking-chambers and heating-walls, are disposed in groups of three, each group having a large middle gas-generator 63 flanked by two smaller air-regenerators 64, 64. The gas-regenerators 63 are adapted for preheat- 75

ing poor or weak gas, such as producer gas or blast furnace gas, but are also adapted for pre-heating air when the ovens are being fired with strong gas, such as their own distillation gases which do not require regenerative preheating. The air-regenerators 64 are adapted for preheating air and in each group they flank the middle gas-regenerator 63 which is thereby isolated from the regenerators of the aforesaid groups that are simultaneously operating for down-flow or out-flow of waste gases, such isolating of the gas regenerators serving to eliminate possibilities of leakage of gas into the countercurrent flow of waste gases under lower pressure in said adjacent regenerator groups. At any given time, alternate groups of regenerators operate for up-flow of gas and air and the intermediate groups for down-flow of waste gases, these relations being reversed at each period of reversal of the regenerative system (as set forth, for instance, in my Patent 1,678,802 which shows similar triple groups of regenerators). Each gas-regenerator 63 at its top communicates through two ducts 71, 71 with heating-flues in heating-walls that are on respectively opposite sides of the coking-chamber that is directly above such gas-regenerator; and the two air-regenerators 64 that flank said gas-regenerator each communicate respectively, through ducts 78, with the heating flues in one of said two heating-walls that are both in communication with said gas-regenerator. The sets of heating-flues, for instance 65, in such two heating-walls, operate simultaneously in the same direction in respect of each other, for instance, for up-flow, while the intermediate sets of heating flues, for instance 66, in such two heating walls, operate simultaneously for down-flow and are respectively connected by similar ducts with the respectively adjacent regenerators of the down-flow regenerator groups that are located on either side of the regenerator group that is then as aforesaid feeding the up-flow heating-flues in the same pair of heating-walls. The groups of regenerators are separated from each other by the oven supporting pillar-walls 79 that are respectively located below the heating-walls served by the adjacent regenerators of the groups on either side of such pillar-walls. In each triple group of regenerators the gas and air regenerators are separated from each other by partition-walls 89 which are of lighter structure than the pillar-walls 79 between the adjacent groups of regenerators. The above-described regenerators are in two series lengthwise of the battery, one series for the pusher-side half of the battery and the other series for the coke-side half of the battery, the cross-regenerators of the one series abutting end for end, along the lengthwise middle of the battery, with the corresponding cross-regenerators of the other series and being separated therefrom by the median longitudinal partition wall 81 that extends longitudinally along the middle of the series of coking-chambers and heating-walls comprised in the superstructure above the regenerators. The gas-regenerators in the pusher-side series and coke-side series respectively are fed with gas from gas-mains that extend along the pusher-side and coke-side respectively of the battery (after the manner of the other oven that is shown in Fig. 1). Each gas-regenerator has a wide sole-channel 84 extending lengthwise of the regenerator under its checkerbrick, and each air-regenerator has a narrower sole-channel 85

extending lengthwise of it under its checkerbrick. All of the sole-channels are provided with gas and air and waste gas connections constructed and operated in the manner described in respect of the other oven that is shown in Fig. 1, and particularly in respect of the manner of operating the oven when fired with poor or weak gas or, alternatively, with strong gas. Curtain-walls 102 subdivide the checkerwork in the regenerators to equalize flow. 10

For alternatively firing the battery with rich gas, such as its own gases of distillation, the base of each heating-flue is provided with a gas-conduit 91 that extends directly downward to and through the foundation-mat 92 that supports the 15 regenerators. All such conduits are provided at their lower exposed ends with the connections and valves and reversing mechanism and rich-gas mains already described in respect of the other oven that is shown in Figs. 1 and 2, except that 20 for each of the halves, the pusher-side half and the coke-side half of each heating-wall in the oven of Figs. 6 to 9, the gas-conduits 91 are provided with two branch-headers that are respectively connected with alternate conduits 91, the 25 one branch header being connected with the odd numbered and the other with the even numbered of such gas conduits, counting them in succession along the heating-wall from either side to the longitudinal middle of the battery. Such 30 two branch-headers and their connections with the gas-mains for the rich gas are operated in alternation, during the alternate periods of reversal of the battery, and respectively serve alternate heating-flues along the heating-walls, the 35 one header serving the odd numbered heating-flues and the other header serving the even numbered heating-flues, counting from the outside to the longitudinal middle of the battery, so as to effect the up-flow and down-flow conditions and 40 relations already described in respect of the hair-pin-flues formed by the two sets of heating-flues in each heating-wall.

The gas-conduits 91, individual to the heating-flues, are placed in the oven supporting pillar-walls 79 that are of a heavy construction tending to minimize possibilities of leakage between such gas-conduits and the regenerators on either side of each such pillar-wall 79. 45

Cross-under ducts 101 disposed transversely 50 under the coking-chambers connect with each other at their lower parts the sets of heating-flues that in alternation and in mutual communication serve for up-flow and down-flow. Each such cross-under duct 101 communicably connects the base of a heating-flue, for instance 66, in one heating-wall with the base of a corresponding heating-flue, for instance 65, in the heating-wall on the opposite side of an intervening coking-chamber 60. In this manner the bottom of each 60 of the heating-flues in a heating-wall that are at any time serving for down-flow is communicably connected, by such cross-under ducts 101, with the bottom of a corresponding one of the heating-flues in an adjacent heating-wall, on the opposite side of an intervening coking-chamber, that are at the same time serving for up-flow, thus connecting the sets of heating-flues in one heating-wall that are operating for up-flow of burning gases with the set in the opposite heating-wall 70 that are operating for down-flow of the combustion products from their contiguous up-flow flues. These down-flowing combustion products in each down-flow heating-flue are in large part led off through the waste gas regenerators then in com- 75

munication with such down-flow set of heating-flues. But a considerable portion of the combustion products down-flowing through such heating-flue is both impelled and drawn through the cross-under duct 101 from the base of such heating-flue over into the corresponding up-burning heating-flue on the opposite side of the intervening coking-chamber, and there will intermix with the up-flow combustion media and the newly formed combustion products in such up-burning flue and will traverse such flue and pass on over to and down the contiguous down-flow flue. And then from the bottom of that down-flow flue a large part of the mixed combustion products will be led off through the waste gas regenerators then in communication with such down-flow heating-flue, but a considerable portion of such combustion products will be both impelled and drawn through the cross-under duct 101 from the base of that down-flow flue back into the corresponding up-burning heating-flue on the opposite side of the intervening coking-chamber and will there intermix with the up-flow combustion media and the newly formed combustion products in such up-burning flue and will traverse such flue and pass over and down into the contiguous down-flow flue from which the circulation just mentioned first started. This will complete a cyclical recirculation through the communicably connected heating-flues on both sides of the intervening coking-chamber. The effects and advantages of and ways of controlling such recirculation are substantially those that have already been described in respect of the like recirculation effected by the cross-under ducts 51 in the other oven that is illustrated in Figs. 1 to 5, and so the manner and purposes of such recirculation need not be discussed further here.

The invention as hereinbefore set forth or exemplified, by said illustrative instances, may be variously embodied or practiced within the scope of the claims hereinafter made.

I claim:—

1. In a coking retort oven, in combination: a series of alternate coking chambers and intermediate heating walls therefor arranged side-by-side in a row, each of said heating walls comprising vertical heating flues, the heating flues of said heating walls being mutually communicably connected so as to provide two sets of flues that are communicably connected together and operable for concurrent upflow of burning gases in one of the sets and downflow of combustion products therefrom in alternation with each other, with flues of one set in some of the heating walls and flues of the other set in others of the heating walls operable concurrently with each other, regenerators communicating with said sets of heating-flues and adapted to serve in alternation for supplying preheated combustion-medium to and withdrawing combustion-products from said two sets respectively, and cross-under ducts disposed longitudinally of said row and under the coking-chambers and connecting the flues of one set with the flues of the other set of the sets of heating flues that are adapted to serve in alternation and are mutually communicably connected to serve for upflow and for downflow, said ducts connecting the flues at their lower parts and being adapted to withdraw portions of the down-flowing combustion-products from each of the sets of heating-flues when operable for downflow of combustion products and discharge such combustion-products into the other set of heating-flues that is then concurrently operable for burning up-flowing

gases, and thereby act to dilute and extend the combustion in the then burning heating-flues.

2. In a coking retort oven, in combination: a series of alternate coking-chambers and intermediate heating-walls therefor arranged side-by-side in a row, each of said heating-walls comprising vertical heating-flues, the heating-flues in each of the heating-walls being communicably connected with heating-flues in another of the heating-walls by cross-over conduits spanning the coking-chambers therebetween so as to provide two sets of heating-flues operable for concurrent upflow of burning gases in one of the sets and downflow of combustion-products therefrom in alternation with each other; regenerators communicating with said sets of heating-flues and adapted to serve in alternation for supplying preheated combustion-medium to and withdrawing combustion-products from said two sets respectively; and cross-under ducts disposed longitudinally of said row and under the coking-chambers and connecting the sets of heating-flues that in alternation and in mutual communication serve for upflow and for downflow, said ducts connecting the flues at their lower parts and being adapted to withdraw portions of downflowing combustion-products from the one set of heating-flues and discharge such combustion-products into the other set of heating-flues, and thereby act to dilute and extend combustion in the other set of heating-flues.

3. In a coking retort oven, in combination: a series of alternate coking-chambers and intermediate heating-walls therefor arranged side-by-side in a row, said heating-walls each comprising a row of vertical heating-flues in which contiguous heating-flues are mutually connected at their tops to form hairpin-flues and so as to provide in the heating walls two sets of heating-flues that are communicably connected together and operable in alternation with each other for concurrent upflow of burning gases in one of the sets and downflow of combustion gases therefrom with the heating-flues of one set alternating in position with the heating-flues of the other set in each heating-wall; regenerators communicating with said sets of heating-flues and adapted to serve in alternation for supplying preheated combustion-medium to and withdrawing combustion-products from said two sets respectively; and cross-under ducts disposed longitudinally of said row and under the coking-chambers and connecting the two sets of heating-flues, said ducts connecting the flues at their lower parts and being adapted to withdraw portions of downflowing combustion-products from the heating flues of one set of each heating-wall and discharge such combustion-products into the heating-flues of the other set in another heating-wall, and thereby act to dilute and extend combustion in the other set of heating-flues.

4. In a coking retort oven, the combination as claimed in claim 1 and in which the regenerators are cross-regenerators below the series of coking-chambers and heating-walls.

5. In a coking retort oven, the combination as claimed in claim 2 and in which the regenerators are cross-regenerators below the series of coking-chambers and heating-walls.

6. In a coking retort oven, the combination as claimed in claim 3 and in which the regenerators are cross-regenerators below the series of coking-chambers and heating-walls.

7. In a coking retort oven, the combination as claimed in claim 1 and having conduits for sup-

plying strong gas to the heating-flues independently of the regenerators.

8. In a coking retort oven, the combination as claimed in claim 2 and having conduits for supplying strong gas to the heating-flues independently of the regenerators.

9. In a coking retort oven, the combination as claimed in claim 3 and having conduits for supplying strong gas to the heating flues independently of the regenerators.

10. In a coking retort oven, in combination: a

series of alternate coking-chambers and intermediate heating-walls therefor arranged side-by-side in a row, each of said heating-walls comprising vertical heating-flues, the heating-flues of

said heating-walls being mutually communicably connected so as to provide two sets of flues operable for concurrent upflow of burning gases in one of the sets and downflow of combustion-products

therefrom in alternation with each other, with flues of one set in some of the heating-walls and flues of the other set in others of the heating-walls operable concurrently with each other; cross-regenerators below the series of coking-

chambers and heating-walls and communicating with said sets of heating-flues and adapted to serve in alternation for supplying preheated combustion-medium to and withdrawing combustion-products from said two sets respectively, the regenerators being disposed in side-by-side groups

adapted in alternation to preheat air and gas for combustion and to recover waste heat from the off-flowing combustion-products, the regenerators for inflow of fuel gas being isolated from regenerators for concurrent outflow of waste gas

by intervening regenerators for simultaneous inflow of air; and cross-under ducts disposed longitudinally of said row under the coking-chambers and connecting the flues of one set with the flues

of the other set of the two sets of heating-flues, said ducts connecting the flues at their lower parts and being adapted to withdraw portions of the downflowing combustion-products from each of the sets of heating-flues when operable for down-

flow of combustion-products and discharge such combustion-products into the other set of heating-flues that is then concurrently operable for burning upflowing gases, and thereby act to dilute and extend the combustion in the then burning

heating-flues.

11. In a coking retort oven, the combination as claimed in claim 10 and having the groups of regenerators each comprised of a pair of air-regenerators flanking an intermediate gas-regenerator that communicates with two sets of heating-flues, said sets respectively communicating with said air-regenerators.

12. In a coking retort oven, the combination as claimed in claim 2 and having the regenerators disposed in groups adapted in alternation to preheat air and gas for combustion and to recover waste heat from the off-flowing combustion-products, the gas-regenerators being isolated from the waste-gas regenerators by intervening air-regenerators during each period of the intermittently reversed flow, the groups of regenerators each comprising a pair of air-regenerators flanking an intermediate gas-regenerator that communicates with two sets of heating-flues, said sets respectively communicating with said air-regenerators.

13. In a coking retort oven, the combination as claimed in claim 3 and having the regenerators disposed in groups adapted in alternation to preheat air and gas for combustion and to recover waste heat from the off-flowing combustion-prod-

ucts, the gas regenerators being isolated from the waste-gas regenerators by intervening air-regenerators during each period of the intermittently reversed flow, the groups of regenerators each comprising a pair of air-regenerators flanking an intermediate gas-regenerator that communicates with two sets of heating-flues, said sets respectively communicating with said air-regenerators.

14. In a coking retort oven, the combination as claimed in claim 10 and having conduits for supplying strong gas to the heating-flues independently of the regenerators.

15. In a coking retort oven, in combination: a series of alternate coking-chambers and intermediate heating-walls therefor arranged side-by-side in a row, each of said heating-walls comprising vertical heating-flues, the heating-flues in each of the heating-walls being communicably connected with heating-flues in another of the heating-walls by cross-over conduits spanning the coking-chambers therebetween so as to provide two sets of heating-flues operable for concurrent upflow of burning gases in one of the sets and downflow of combustion-products therefrom in alternation with each other; cross-regenerators below the series of coking-chambers and heating-walls and communicating with said sets of heating-flues and adapted to serve in alternation for supplying preheated combustion-medium to and withdrawing combustion-products from said two sets respectively, the regenerators being disposed in side-by-side groups adapted in alternation to preheat air and gas for combustion and to recover waste heat from the off-flowing combustion-products, the regenerators for inflow of gas being isolated from regenerators for concurrent outflow of waste gas by intervening regenerators for simultaneous inflow of air; conduits for supplying strong gas to the heating-flues independently of the regenerators; and cross-under ducts disposed longitudinally of said row under the coking-chambers and connecting the two sets of heating-flues, said ducts connecting the flues at their lower parts and being adapted to withdraw portions of downflowing combustion-products from the one set of heating-flues and discharge such combustion-products into the other set of heating-flues, and thereby act to dilute and extend combustion in the other set of heating-flues.

16. In a coking retort oven, in combination: a series of alternate coking-chambers and intermediate heating-walls therefor arranged side-by-side in a row, said heating-walls each comprising a row of vertical heating-flues in which contiguous heating-flues are mutually connected at their tops to form hairpin-flues and so as to provide in the heating-walls two sets of flues operable in alternation with each other for concurrent upflow combustion in one of the sets and downflow of combustion gases therefrom with the heating-flues of one set alternating in position with the heating-flues of the other set in each wall; cross-regenerators below the series of coking-chambers and heating-walls and communicating with said sets of heating-flues and adapted to serve in alternation for supplying preheating combustion-medium to and withdrawing combustion-products from said two sets respectively, the regenerators being disposed in side-by-side groups adapted in alternation to preheat air and gas for combustion and to recover waste heat from the off-flowing combustion products, the regenerators for inflow of gas being isolated from regenerators for simultaneous outflow of waste gas by intervening regenerators for simultaneous inflow of air, conduits

for supplying strong gas to the heating-flues independently of the regenerators; and cross-under ducts disposed longitudinally of said row under the coking-chambers and connecting the sets of heating-flues, said ducts connecting the flues at their lower parts and being adapted to withdraw portions of downflowing combustion-products from the heating-flues of one set of each heating-wall and discharge such combustion-products into the heating-flues of the other set in another heating-wall, and thereby act to dilute and extend combustion in the other set of heating-flues.

17. In a coking retort oven, the combination as claimed in claim 15 and having the conduits for strong gas leading downward to gas-mains underneath the oven, such conduits being placed in supporting walls that are immediately between regenerators adapted to operate for up-flow concurrently with gas up-flow through said conduits.

18. In a coking retort oven, the combination as claimed in claim 16 and having the conduits for strong gas leading downward to gas-mains underneath the oven, such conduits being placed in supporting walls that separate the groups of regenerators.

19. In a coking retort oven, in combination: a series of alternate coking-chambers and intermediate heating-walls therefor arranged side-by-side in a row, each of said heating-walls comprising vertical heating-flues, the heating-flues of said heating-walls being mutually communicably connected so as to provide two sets of flues that are communicably connected together and operable for concurrent in-flow of burning gases in one of the sets and off-flow of combustion products therefrom in alternation with each other, with flues of one set in some of the heating-walls and flues of the other set in others of the heating-walls operable concurrently with each other; regenerators communicating with said sets of heating-flues and adapted to serve in alternation for supplying preheated combustion-medium to and withdrawing combustion-products from said two sets respectively; and cross-around ducts disposed longitudinally of said row of coking chambers and connecting the flues of one set with the flues of the other set of the two sets of heating-flues that are on opposite sides of the coking-chambers crossed around by said ducts, said ducts being adapted to withdraw portions of the off-flowing combustion-products from each of the sets of heating-flues when operable for off-flow of combustion-products and discharge such combustion-products into the other set of heating-flues that is then concurrently operable for burning in-flowing gases, and thereby act to dilute and extend the combustion in the then burning heating-flues.

20. In a coking retort oven, in combination: a series of alternate coking-chambers and intermediate heating-walls therefor arranged side-by-side in a row, each of said heating-walls comprising vertical combustion-flues, the flame-flues being communicably connected together at their upper parts into pairs of groups for upflow combustion in one member of the pair or group and downflow of combustion-products therefrom in the other member of the pair or group in alternation, each member of each pair lying on the opposite side of a coking-chamber from the other

member of the same pair, regenerators communicating with the combustion-flues at the lower parts thereof, and cross-under ducts communicably connecting the lower parts of flues of each group of a pair of groups with the lower parts of the flues of the other group of the same pair, said cross-under ducts crossing under coking-chambers intervening the groups connected by the cross-under ducts and said cross-under ducts being adapted to withdraw portions of the products of combustion from some of the groups of flues when operable for upflow combustion and discharge such combustion-products into the flues of the other groups connected therewith by the cross-under ducts and concurrently operable for upflow combustion and thereby act to dilute and extend the combustion in the flues when operable for upflow combustion.

21. In a coking retort oven, in combination: a series of alternate coking-chambers and intermediate heating-walls therefor arranged side-by-side in a row, each of said heating-walls comprising vertical combustion-flues, the flame-flues being communicably connected together at their upper parts into pairs of groups for upflow combustion in one member of the pair or group and downflow of combustion-products therefrom in the other member of the pair or group in alternation, each member of each pair lying on the opposite side of a coking-chamber from the other member of the same pair, regenerators communicating with the combustion-flues at the lower parts thereof, and cross-under ducts communicably connecting the lower parts of flues of each group of a pair of groups with the lower parts of the flues of a group operable for concurrent gas flow in reverse direction, said cross-under ducts crossing under coking-chambers intervening the groups connected by the cross-under ducts and said cross-under ducts being adapted to withdraw portions of the products of combustion from some of the groups of flues when operable for upflow combustion and discharge such combustion products into the flues of the other groups connected therewith by the cross-under ducts and concurrently operable for upflow combustion and thereby act to dilute and extend the combustion in the flues when operable for upflow combustion.

22. In a coking retort oven, a coking-chamber, combustion heating means therefor comprising vertical combustion flues operable in alternation for upflow of combustion of gas and air and downflow of off-flow waste gas, the combustion flues being operatively disposed in groups with communicable connections at their upper and lower ends in such manner that part of the flues of each group are operable for upflow combustion while the remaining flues of the same groups are operable to receive and flow the waste gas thereof downwardly, and part of the waste gas may pass through the lower communicable connections of a group from the flues operable for downflow into the flues of the groups operable for upflow while the remaining part of the waste gas is exhausted from the groups, said lower communicable connections comprising ducts in the bottoms of the vertical flues and opening into the vertical flues in a substantially vertical direction.

JOSEPH BECKER.
